UNITED STATES PATENT OFFICE

JOHN W. OSBORNE, OF ALSEY, ILLINOIS

MACHINE FOR MIXING ROAD MATERIAL

Application filed February 1, 1927. Serial No. 165,138.

This invention relates to road building machines and particularly to a mixing apparatus especially adapted for use with a road carpeting machine and has for its object the 5 production of a simple and efficient apparatus for facilitating the mixing of materials used in the construction of roads.

Other objects and advantages of this invention will appear throughout the following 10 specification and claim.

In the drawings:

Figure 1 shows, in side elevation, the heating and mixing machine for a road carpeting composition.

15 Figure 2 shows the machine disclosed in Figure 1, in vertical longitudinal section.

Figure 3 is a transverse section taken upon the line 3—3 of Figure 2.

20 Figure 4 is a vertical transverse section taken upon the line 4—4 of Figure 2.

Referring now to the drawings in detail wherein like numerals of reference indicate corresponding parts throughout the several views, the mixing machine for the road covering composition comprises a wheeled supporting structure consisting of a pair of elongated parallel I beams 1 supported at their ends by the front and rear axles 2 and 3 respectively, each of which axle carries in the usual manner, traction wheels 4.

25 Extending transversely of the beams 1, upon the under side of the same, is a short supporting beam 5 which supports at each end, one end of a forwardly extending outer beam 35 6, the forward ends of these beams 6 resting upon the front axle 2.

Resting upon the beams 1 and 6 is a mixing tank indicated as a whole by the numeral 7, the floor 8 of which tank is raised above the 40 lower edge thereof setting up the chamber 9 therebeneath. The tank may be secured to the supporting beams in any appropriate manner, the means here shown comprising an annular body of L-shaped cross section as 45 indicated by the numeral 10, one flange of which is riveted to the wall of the tank while the other flange is secured to the beams.

50 The wall of the tank below the floor 8 is provided with a plurality of apertures 11 and also has a number of doors opening there-

through as indicated at 12, the doors being hinged to the wall as at 13 and having catches 14 for maintaining them in closed position.

The top of the tank 7 is covered by the pair of cover members 15 which are hinged to the centrally positioned plate 16 extending across the top of the tank. 55

Positioned within the tank centrally there-of is a fixed vertically positioned post 17 having a longitudinally extending passage there-through and merging at its lower end in a circular plate 18, which is riveted to the bottom 8 of the tank. The upper surface of the plate 18 is provided with an annular groove which surrounds and is spaced from the post 17 as shown in Figure 2. Fixed to one of the I beams 1 beneath the central portion of the tank, is a bearing 20 which supports one end of a vertical shaft 21, which shaft extends upwardly through the bottom 60 of the tank and through the passage in the post 17, projecting above the upper end of the post. 65

Surrounding the post 17 is a cylinder or sleeve 22 the lower end of which fits into the annular groove 19 while the upper edge is substantially in the same plane as the top of the post. The upper end of the post and cylinder has placed thereover the cap plate 23, the under face of which is recessed to receive the 70 post and cylinder and also has a central bore formed therein for the reception of the upper end of the shaft 21, which is secured thereto in any appropriate manner. 75

Secured against the wall of the cylinder 22 80 adjacent the upper and lower ends and at diametrically opposite points thereon are the ends of oppositely directed parallel mixer arms 24, the arms on one side of the cylinder 85 constituting a pair and each having bolt connection with the opposed arm at the opposite side of the cylinder, as indicated at 25, each pair of arms being connected by a plurality of spaced parallel slats 26. It will thus be seen that the cylinder carries a pair of oppositely directed mixing paddles which extend from the cylinder to a point adjacent the wall of a tank 7. Extending horizontally beneath the tank 7 from a point adjacent the center thereof outwardly to one side of the 90 95 100

structure, is a shaft 27 mounted in the bearings 28 carried upon certain of the beams located beneath the tank. The inner end of the shaft 27 has a beveled gear secured thereto as indicated by the numeral 29 which gear meshes with the beveled gear 30 secured to the lower end of the vertical shaft 21. The outer end of the shaft 27 carries the belt pulleys 32, and carried upon the supporting beams for the tank, forwardly of the same is a pair of beam members 33 designed to be used as a supporting base for a power engine (not shown), from which power may be transmitted to the pulleys 32, as indicated in dotted lines in Figure 1.

15 The tank 7 has the wall thereof provided, adjacent the bottom, at the forward part, with an outlet opening 34 and secured to the tank around this opening is an outlet 35.

20 Having thus described my invention, what I claim is:

In a road carpeting machine, a material carrying tank, a standard mounted in the tank, a shaft extending through the standard and through the bottom of the tank, a base for the standard having an annular recess in its upper face, a sleeve surrounding the standard and having its lower end positioned in said recess, a cap overlying the upper ends 25 of the standard and sleeve and secured to the sleeve and shaft, an upper pair and a lower pair of arms extending horizontally from the sleeve, the inner end portions of each pair of arms being arranged in contact 30 with diametrically opposite sides of the sleeve, bolts passing through the arms of each pair in close proximity to the sleeve to secure the arms to the sleeve, vertical slats secured to the arms, and driving means connected to the 35 shaft.

40 In testimony whereof I affix my signature.
JOHN W. OSBORNE.
